UNITED STATES PATENT OFFICE.

ALBERT CARROLL WOOD AND JAMES ALEXANDER McMULLAN, OF
PHILADELPHIA, PENNSYLVANIA.

BATTERY-PLATE MOLD.

SPECIFICATION forming part of Letters Patent No. 770,139, dated September 13, 1904.

Application filed February 20, 1902. Serial No. 94,984. (No model.)

To all whom it may concern:

Be it known that we, ALBERT CARROLL WOOD and JAMES ALEXANDER McMULLAN, citizens of the United States, residing at Philadelphia, in the county of Philadelphia and State of Pennsylvania, have invented certain new and useful Improvements in Battery-Plate Molds, of which the following is a specification, reference being had therein to the accompanying drawings.

Our invention has for its object the economic and rapid formation of storage-battery plates or electrodes, which are of novel and very desirable construction.

In order that our invention may be more easily understood, we have in the accompanying drawings illustrated the mechanism employed for molding or casting the electrodes.

In such drawings, Figure 1 is a plan view of one section of a mold in which are placed nine holders for the strips of lead tape which enter into the construction of the electrode to be formed. Fig. 2 is a transverse section taken on the line 2 2 of Fig. 1. Fig. 3 is a top plan view of one of the strip-holders detached. Fig. 4 is a top plan view of a somewhat different form of strip-holder. Fig. 5 is a side view of one of the strips of lead, and Fig. 5^a an edge view of the same strip. Fig. 6 is a detail sectional view illustrating the method of procedure followed in making an electrode of more than ordinary thickness. Fig. 7 is a plan view of a completed electrode made according to our invention.

The electrode which is illustrated in Fig. 7 consists of a frame of suitable material, such as lead or an alloy of lead and a series of strips of thin lead or "lead tape," as this material is commonly known in the art, arranged parallel to each other and in groups or masses which are separated from each other by cross-pieces of the frame. The masses or groups of lead strips are preferably so arranged that those of one mass are disposed at right angles to those of the next adjacent mass, as this construction is found to reduce the danger of the electrode buckling or warping.

The outer rim of the frame of the electrode

we have designated *a*, and the intermediate partitions or cross-pieces as *a'*. The strips of lead tape are designated *b*. The strips of each set or group are parallel with each other, are situated so as to be separated a short distance from each other, and the ends of each strip are united with the contiguous parts *a* or *a'* of the frame by being fused therewith, so that the completed article is an integral structure.

Heretofore it has been a matter requiring much labor and the exercise of considerable skill to properly arrange the lead strips in the frame, particularly when an electrode of large size is to be produced. One of the objects of our invention is to reduce the labor and skill incident to the proper arrangement of the lead strips relative to each other and to the electrode as a whole and to facilitate the casting of such electrodes and at the same time insure absolute uniformity in the resulting product.

The mold which we employ is formed of two sections C and D, which are adapted to be brought together face to face, as indicated in Fig. 2, when a casting is to be made. Each section is provided with a central cavity or recess of a size or contour corresponding with that of the electrode which is to be produced. Each section is provided with suitable channels *e*, through which the fluid metal is forced and which serve to conduct it to the mold-chamber.

F indicates a strip-holder. It consists of a suitable piece of metal, preferably steel, of rectangular shape and having one face channeled or grooved, as indicated at *f*. The width of each groove is sufficient to receive and support one of the lead strips *b*.

We prefer that each of the strip-holders should have a solid back *f'*, from which project the ribs or partitions *f''*, which separate the grooves *f*. The ends of each partition and the outer faces of the outermost or side partitions are slightly beveled in order to permit the strip-holder to be drawn from the mold. It will be seen by referring to Figs. 1 and 3 that the base portion *f'* extends lat-

erally in each direction a little beyond the grooved portion of the holder, so that when a series of holders are arranged in the mold, as represented in Fig. 1, there will be channels or free spaces between the strip-holding grooved portions of the several strip carriers or holders.

The lead strips *b* are a little longer than the grooves *f*, so that when they are placed in such grooves their ends project slightly beyond the ends of the ribs or partitions *f'* and extend into the channels or passages *h* between the holders.

The strip-holders bear a definite relation in size to the size of the chambers or recesses in the molds *C* and *D*, so that a given number of such holders, as four or six or nine, the latter number being represented in the drawings, will completely fill the mold-chamber. We prefer that the strip-carriers should be arranged in the mold as shown in Fig. 1—that is to say, with the grooves in one holder at right angles to those next adjacent to it.

From this description the process of forming an electrode will be readily understood. The strip-holders are filled with strips, which may be done by unskilled workmen, and the holders thus filled are placed in the molds in the manner indicated in Fig. 1, the strips carried by each section projecting outward into the channels *h*, formed between the strip-holders. The strip-holders being thus arranged, the two parts of the mold are brought together and the metal poured in in the usual manner. It will be understood that the metal to form the frame follows the channels *h* and *h'* and that in so doing it surrounds the ends of the strips, which project into these channels or passages and fuses them, so that when the metal cools and becomes solid each strip has been united at each of its ends with the mass of metal which constitutes the supporting-frame. After the metal becomes hard the parts of the mold *C* and *D* are separated, the strip-holders are drawn out, and the completed electrode is produced.

We prefer that the ends of the strips *b* should be serrated, as indicated at *g*, in order to insure better and more certain union of the strip with the frame.

It is often desirable to use lead strips of corrugated shape, and when such strips are to be used we prefer to employ a holder like that represented in Fig. 4. In this form of holder the partitions *f''* extend but part way across the face of the base portion *f'*, as clearly indicated in Fig. 4. The side partitions *f'''* of course are continuous from end to end of the plate to prevent the fluid metal from entering the central open part of the holder. In using corrugated strips we prefer to corrugate a portion of their length only, such strips being arranged as indicated in Fig. 4, where two corrugated strips are represented as being in plan.

It is sometimes desired to make an electrode of unusual thickness. This can be done by employing two sets of strip-holders and arranging them as shown in Fig. 6—that is to say, so that the grooved faces of the holders shall come opposite to each other. The strips, which are twice the width of those usually employed, will each be supported in the channels formed by the registering grooves of the two opposing strip-holders. It will be understood that the recesses formed in the molds will be different in size and depth from those illustrated in Fig. 2 when two sets of strip-holders are used in the manner illustrated in Fig. 6 for the purpose of making a thick electrode, but it is deemed unnecessary to illustrate the molds further from what is shown in Fig. 6.

It will be observed that each holder comprises a base upon which a group of strips is supported on edge, abutments carried by the base and against which the outermost strips of the group rest, such abutments being represented as formed by the outermost ribs or partitions, and means carried by the base for properly positioning and holding against lateral movement the holder when in the mold, such positioning and holding means being formed in the embodiment of our invention herein illustrated by those portions of the base that project laterally beyond the group of strips supported on the base. These means for holding the strip-holders in the mold-section are arranged below the lower edges of the strips when the latter are horizontally disposed, as represented in the drawings, and preferably have their upper faces in the same plane as the lower faces of the group of strips, as by this arrangement the completed electrode has the faces of all of its parts—that is, of the rigid frame and the groups of strips—in a common plane. Such a holder may be and preferably is square in outline and is adapted to hold a group of strips that is also square. This enables us to use holders that are duplicates of each other, and permits them to be quickly and easily arranged in the mold-sections in any desired relations, such as that shown in the drawings, where the strips of adjacent groups are at right angles to each other or with the strips of all the groups parallel. By constructing the holder so that it receives and holds a group of strips that is square in outline we can produce an electrode that does not contain undesirably large open spaces between the strips and the bars of the rigid cast frame, as has heretofore been incident to electrodes formed with a rigid cast frame and groups of lead strips incorporated therein, but rather has the spaces between the strips themselves and between them and the bars of the frame of substantially uniform size.

What we claim is—

1. A mold adapted for use in the casting of

electrodes for secondary batteries, comprising a holder adapted to support a series of lead strips edgewise and substantially parallel with each other, the said holder having formed in its 5 face a series of open-ended grooves, and there being arranged adjacent to the opposite open ends of each of the said grooves channels through which the fluid metal flows, whereby the strips are held securely and are caused to 10 be intimately united at each end by fusion with the frame of the electrode, substantially as set forth.

2. A mold adapted for use in the manufacture of electrodes for secondary batteries, comprising a plurality of holders each adapted to support a series of lead strips edgewise and substantially parallel with each other and with their opposite ends exposed, the face of each 15 holder having formed therein a series of open-ended grooves for the lead strips, and there being channels to receive the fluid metal from which the frame of the electrode is formed adjacent to the opposite open ends of each of the 20 grooves in the faces of the holders, substantially as set forth.

3. A holder for supporting strips of lead edgewise, having a solid back or base portion and a grooved face in which the strips are placed, the back portion extending laterally 25 beyond the open ends of the grooves formed in the face thereof, substantially as set forth.

4. The combination with a recessed mold, of a series of holders adapted to support thin strips of lead edgewise in the mold, such 30 holders being rectangular and having solid base portions, and grooved or channeled top portions in which the said strips are placed, the base portions of the holders extending laterally beyond the grooved parts thereof, 35 whereby when two of such holders are placed side by side a channel is formed between their grooved portions, substantially as set forth.

5. A holder adapted to support corrugated strips of lead in the manufacture of electrodes 40 for secondary batteries having a solid back, and a grooved face formed of the short partitions f^2 separated from each other by grooves adapted to receive the lead strips, and the continuous side partitions f^3 , substantially as set 45 forth.

6. In a mold adapted for use in the manufacture of electrodes for secondary batteries, a pair of opposite mold-sections and means 50 for holding strips of material which are to be incorporated into the electrode on edge, and in independent groups, during the casting operation, such means comprising groups of ribs projecting outward from one of the mold-sections and arranged to form grooves in which 55 the strips are held, the said groups of ribs being arranged in a common horizontal plane,

and separated from each other by channels, substantially as set forth.

7. The herein-described mold adapted to be used in the casting of electrodes for secondary 65 batteries, comprising a pair of mold-sections adapted to be closed together face to face, and a series of strip-holders formed by ribs which project outward from one of the mold-sections, the ribs being arranged in groups separated 70 from each other by channels, the outermost ribs of each group constituting closed bounding-walls for the contiguous channels, and the ribs of each group being disposed to form grooves between them, the opposite ends of 75 such grooves opening into channels at opposite sides of the group of ribs, substantially as set forth.

8. The herein-described casting apparatus for use in the manufacture of electrodes for 80 secondary batteries, comprising a pair of opposite mold-sections and holders for strips of material to be incorporated into the mold, such holders comprising two sets of ribs carried by the opposite mold-sections and arranged to 85 come opposite each other when the mold-sections are closed, whereby the strips are held, partly by the holders in one mold-section and partly by the holders in the other section, substantially as set forth.

9. A holder for supporting metallic strips which are to be incorporated into an electrode, having a base portion and ribs rigidly secured to one face thereof, the base portion extending in all directions beyond said ribs, whereby 95 when the holder is inserted in a mold there will be a channel for metal entirely surrounding said ribs, substantially as set forth.

10. A holder of the class described for supporting metallic strips edgewise, having a solid 100 base portion and the partitions f^3 projecting upwardly therefrom and adapted to have the metallic strips arranged between them, said base portion extending beyond the ends and the outermost sides of said partitions, substantially as set forth.

11. A holder of the class described for supporting metallic strips edgewise, having a solid back or base portion, the partitions f^3 , f^3 , 110 projecting from one face thereof and arranged near opposite ends of said base portion, and two sets of ribs f^2 , f^2 arranged between said partitions f^3 , f^3 , one set at either side of the said base portion, substantially as set forth.

In testimony whereof we affix our signatures 115 in presence of two witnesses.
